UNITED STATES PATENT OFFICE.

WILLIAM SHEAHAN, OF OREGON CITY, OREGON.

CLUTCH FOR PAPER-SPOOLS.

1,110,651.

Specification of Letters Patent. Patented Sept. 15, 1914.

Application filed April 22, 1911. Serial No. 622,826.

To all whom it may concern:

Be it known that I, WILLIAM SHEAHAN, a citizen of the United States, and a resident of Oregon City, Clackamas county, State of Oregon, have invented a new and useful Improvement in Clutches for Paper-Spools, of which the following is a specification.

This application being intended as a substitute for my prior application filed December 31, 1910, Serial No. 600,350.

This invention relates primarily to devices for clamping the spool of a roll of paper on the shaft on which it is mounted. As well known, such spools are commonly made of wood, iron or paper, but the latter is preferred for its cheapness of manufacture, and saving of freight in transportation, because of its greater lightness. The devices used for clamping the spool on the shaft, however, impose upon it undue wear. In this connection my invention has for its object to provide clamping means which will not impose undue wear on a paper spool; and, furthermore, will insure that the spool will run true. The particular features of my invention, with regard to its use for either purpose, will be taken up in detail in the body of this specification.

In the drawings:

Figure 1 is a sectional elevation illustrating my invention as practically applied for clamping the paper spool on the shaft, the device being shown as appearing before the wedges are expanded to clamp the spool; Fig. 2 shows an assembly of all the devices comprised within my invention, with parts broken away and parts in section; Fig. 3 is a transverse sectional detail of one of the wedges of my device, the section being taken on the plane of the arrow A in Fig. 1; and this figure illustrates the means provided for automatically locking the outer end of one of the wedges with the nut for the purpose explained in the body of the specification; Fig. 4 is a cross section approximately taken on a line B—B of Fig. 1; and Fig. 5 is a perspective detail of one of the segmental wedges.

The shaft, *a*, is understood to be rotatably journaled at its ends in suitable boxing, not shown. It is formed with a flat face *b*, so as to restrain the member mounted thereon against rotation. Longitudinally slidably on the shaft, *a*, is mounted a sleeve *c*, of uniform diameter at one end (*d*), which end is provided with a peripheral thread *e*, and the

opposite end *f* is formed with a series of peripheral conical steps. The eye of the sleeve *c* conforms to the peripheral contour of the shaft *a*, so that it will not rotate on the latter. On the threaded end of the sleeve *c* is mounted a nut *h*, made with a peripheral flange *i*, provided on the interior with a rib *j*.

g is the spool preferably made of paper, for reasons stated. Within the spool *g* are inserted a series of segmental wedges *p*, provided on their inner faces with bevel steps *p'*, corresponding with the conical surfaces *f* of the sleeve *c*, as illustrated in Fig. 1. While the drawing shows four wedges being used, the number of the latter is immaterial, since a greater or lesser number would answer just as well if the other parts of my device are correspondingly arranged. The peripheral conical surfaces of the sleeve *c* and the related surfaces of the segmental wedges *p* must be made in short steps having a steep inclination, in order that the linear displacement, resulting from a short longitudinal movement of the sleeve and segmental wedges against each other, will cause an almost full expansion of my clutch. The wedges *p* are made at their outer ends with a flange *p*², formed with a circumferential groove *r*, corresponding to the inner rib *j* of the flange *i* of the nut *h*. In order that my device will work properly, it is necessary that the cone-faced exterior of the sleeve *c* and the outer and inner faces of the wedge *p* are accurately made, so that the outer faces of the wedge segments will represent a true circle throughout their lengths while climbing and resting on the cone-faced exterior of the sleeve *c*. I prefer to construct the cone-faced exterior of the sleeve and the beveled-faced exterior of the wedges *p* in steps, as shown in Fig. 1, so as to obtain a steeper inclination, and thereby obtain a quicker expansion action.

The flange of the nut *h* is provided with a lock pin *k*, formed with a bent head and with a web *t*, adapted to be inserted in a cavity *u*, provided in the flange *i* of the nut *h*. The lower end of the lock pin *k* is threaded and has mounted on it a collar *l*, on which is seated the lower end of a coil-spring *m*, operating to normally project the lock pin *k* into the cavity *s* of the groove *r* of the flange-head *p*² of the wedges *p*.

The purposes of the devices last described is to take care of an occasion when the clutch

has not been set up sufficiently tight, for under such circumstances the segmental wedges p would have a tendency to rotate with the spools on the cone-faced exterior 5 of the sleeve c , because the contact between the core of the spool and the outer faces of said wedges is greater than that between the inner faces of the latter and the cone-faced exterior of the 10 sleeve c . If this should happen, the lock pin k of the nut h would enter the cavity s of a segmental wedge and by thus locking such parts together the rotation of the segmental wedges will rotate the nut on the 15 thread of the sleeve c and draw up the latter sufficiently to cause the wedges to be properly expanded and clamp the spool. The providing of a cavity s in one of the 20 wedges is however, merely illustrative of means for connecting the nut h and the segmental wedges for the purpose explained. The lock-pin k may also be projected between two adjacent segmental wedges. If the nut h should be moved to the inner 25 end of the thread on the sleeve c without having accomplished the full expansion of the segmental wedges, then the lock-pin, having engaged with one wedge, or being projected between two wedges, will hold the 30 wedges against rotation on the sleeve, and the frictional contact between the outer faces of the wedges and the core of the spool will generally be sufficient to hold the clutch against rotation in the spool. The lock-pin 35 k may be released by merely lifting it against the tension of the coil-spring m , and so arranging it that the web t will be seated crosswise of, instead of in, the cavity u . While both the sleeve c and the wedge 40 segments p move relatively, yet by reason of the greater friction being between the outer faces of the segmental wedges and the spool g , the sleeve c does all the traveling to and fro on the shaft a , during the operation of 45 clamping and releasing the spool.

In order to limit the longitudinal play of the sleeve c and the spool thereon clamped on the shaft a , I use a set collar as v , shown in Fig. 2, at one end, and a set collar w at 50 the opposite end, the latter provided with an arm z , adjustable by a set screw y , since it is my object to make my device adaptable to all conditions. To facilitate the rotation of the nut h , it is provided with spanner 55 holes z .

One of the particular advantages of my device is that the segmental wedges are expanded equally, and there is no danger of tearing the surface of the core of the spool, 60 as there is no torsional movement.

I claim:

1. The combination with a shaft, of a non-rotatable sleeve longitudinally slidable on said shaft; one end of said sleeve provided 65 with a peripheral thread and the opposite

end being made cone-faced; a nut on the threaded end of the sleeve; segmental wedges each formed bevel faced on the interior whereby it is adapted to ride on the cone faced exterior of said sleeve; means 70 for engaging the outer ends of said wedges with the nut; and means for automatically engaging said nut with said wedges, when by reason of looseness the latter rotate on the sleeve with the spool. 75

2. The combination with a shaft, of a non-rotatable sleeve longitudinally slidable on said shaft; one end of said sleeve provided with a peripheral thread and the opposite end being made cone-faced; a nut on the 80 threaded end of the sleeve; segmental wedges each formed bevel faced on the interior whereby it is adapted to ride on the cone faced exterior of said sleeve; means 85 for engaging the outer ends of said wedges with the nut; means for automatically engaging said nut with said wedges, when by reason of looseness the latter rotate on the sleeve with the spool; and means limiting the longitudinal movement of the sleeve on 90 the shaft. 95

3. The combination with a shaft, of a sleeve longitudinally slidable on said shaft; the shaft and the core of said sleeve made with engaging faces preventing the latter 95 rotating on the shaft; one end of said sleeve provided with a peripheral thread and the opposite end being made with a series of peripheral conical steps; a nut on the 100 threaded end of the sleeve; segmental 105 wedges each formed with a series of bevel faced portions on the interior whereby it is adapted to ride on the cone faced exterior of said sleeve; said wedges formed with a peripheral flange at the outer ends and 110 whereby they are engaged with the flange of said nut; means for automatically engaging said nut with said wedges, when by reason of looseness the latter rotate on the sleeve with the spool; and means limiting 115 the longitudinal movement of the sleeve on the shaft. 120

4. The combination with a shaft, of a sleeve longitudinally slidable on said shaft; the shaft and the core of said sleeve made 115 with engaging faces preventing the latter rotating on the shaft; one end of said sleeve provided with a peripheral thread and the opposite end being made with a series of peripheral conical steps; a nut on the threaded end of the sleeve; segmental wedges each formed with a series of bevel faced portions on the interior whereby it is adapted to ride on the cone faced exterior of said sleeve; said wedges formed with a peripheral flange 125 at the outer ends and whereby they are engaged with the flange of said nut; said peripheral flange of the nut being provided with a spring-controlled lock pin and the outer flange of one of said wedges being 130

provided with a related cavity for the purpose set forth; and means limiting the longitudinal movement of the sleeve on the shaft.

5. The combination with a shaft, of a sleeve longitudinally slidable on said shaft; the shaft and the core of said sleeve made with engaging faces preventing the latter rotating on the shaft; one end of said sleeve provided with a peripheral thread and the opposite end being made with a series of peripheral conical steps; a nut on the threaded end of the sleeve; segmental wedges each formed bevel faced on the interior whereby it is adapted to ride on the cone faced exterior of said sleeve; said wedges formed with a peripheral flange at the outer ends and whereby they are engaged with the flange of said nut; said peripheral flange of the nut being provided with a spring-controlled lock pin and the outer flange of one of said wedges being provided with a related cavity for the purpose set forth; and means limiting the longitudinal movement of the sleeve on the shaft.

6. In a clutch, the combination of a sleeve; one end of said sleeve provided with a peripheral thread and the opposite end being made with a series of peripheral conical steps; a nut on the threaded end of the sleeve; segmental wedges each formed bevel faced on the interior whereby it is adapted to ride on the cone faced exterior of said sleeve; said wedges formed with a peripheral flange at the outer ends and whereby they are engaged with the flange of said nut; and means for automatically engaging said nut with said wedges, when by reason of looseness the latter rotate on the sleeve with the spool.

7. In a clutch, the combination of a sleeve; one end of said sleeve provided with a peripheral thread and the opposite end being made with a series of peripheral conical steps; a nut on the threaded end of the sleeve; segmental wedges each formed with a series of bevel faced portions on the interior whereby it is adapted to ride on the cone faced exterior of said sleeve; said wedges formed with a peripheral flange at the outer ends and whereby they are engaged with the flange of said nut; and said peripheral flange of the nut being provided with a spring-controlled lock pin and the outer flange of one of said wedges being provided with a related cavity for the purpose set forth.

8. In a clutch of the class described, the combination of a sleeve adapted to be mounted on a shaft, said sleeve formed with an exterior conical periphery; a wedge element formed with an interior conical periphery whereby it is adapted to ride on said conical surfaces of said sleeve; means for moving said sleeve and said wedge element longi-

tudinally on each other; and means for engaging said wedge element with said means for automatically effecting said longitudinal movement when a roll supported by the clutch becomes loose.

9. In a clutch of the class described, the combination of a sleeve adapted to be mounted on a shaft, said sleeve formed with an exterior conical periphery; a segmental wedge formed with an interior conical periphery whereby it is adapted to ride on said conical surfaces of said sleeve; means for moving said sleeve and said segmental wedge longitudinally on each other; and means for engaging said segmental wedge with said means for automatically effecting said longitudinal movement when a roll supported by the clutch becomes loose.

10. In a clutch of the class described, the combination of a sleeve adapted to be mounted on a shaft, said sleeve formed with a series of peripheral conical surfaces arranged in short steps of steep inclination; a wedge element formed with a series of interior peripheral conical steps arranged relatively to said peripheral surface of the sleeve; means for moving said sleeve and said wedge element longitudinally on each other; and means for engaging said wedge element with said means for automatically effecting said longitudinal movement when a roll supported on the clutch becomes loose.

11. In a clutch, the combination of a sleeve adapted to be mounted on a shaft, said sleeve formed with a series of peripheral conical surfaces arranged in short steps of steep inclination; a segmental wedge formed with a series of interior peripheral conical steps arranged relatively to said peripheral surface of the sleeve; means for relatively moving said sleeve and said segmental wedge longitudinally on each other; and means for automatically engaging said segmental wedge with said means for effecting said longitudinal movement when by reason of looseness the segmental wedge rotates on the shaft and to thereby actuate said moving means.

12. In a clutch, the combination of a sleeve adapted to be mounted on a shaft, means preventing the rotation of the sleeve on the shaft, said sleeve formed with a series of peripheral conical surfaces arranged in short steps of steep inclination; a wedge element formed with a series of interior peripheral conical steps arranged relatively to said peripheral surface of the sleeve; means for relatively moving said sleeve and said wedge element longitudinally on each other; and means for automatically engaging said segmental wedge with said means for effecting said longitudinal movement when by reason of looseness the segmental wedge rotates on the shaft and to thereby actuate said moving means.

13. In a clutch of the class described, the combination of a sleeve adapted to be mounted on a shaft and provided with a peripherical conical wedge shape surface, a wedge element formed with an interior wedge surface arranged relatively to the wedge surface on the sleeve and coöperating therewith to create a binding action to lock the wedge element and the sleeve together, means for holding the wedge surfaces of the wedge element and the sleeve in binding relation, and means coöperating with the aforesaid means for automatically operating the wedge element to take up wear of a roll supported by said sleeve.

14. In a clutch of the class described, the combination of a non-rotatable sleeve formed with a peripherical conical wedge shape surface and provided with screw threads, a wedge element formed with an interior wedge surface arranged relatively to the wedge surface on the sleeve and coöperating therewith, means operating on the threads to force the wedge element inwardly to cause the wedge surfaces to engage, and means between the aforesaid means and the wedge element to cause rotation of the first mentioned means to automatically move the wedge element to bind against a roll supported thereon when the latter becomes loose.

15. In a clutch of the class described, the combination of a non-rotatable sleeve adapted to be mounted on a shaft and provided with a peripherical conical wedge shape surface, a wedge element formed with an interior wedge surface arranged relatively to the wedge surface of the sleeve and coöperating therewith, means engaging the sleeve to operate same, said means having a part which lies adjacent the wedge element, and an interlocking device carried by said part and adapted to engage the wedge element to automatically take up wear of a roll supported by the clutch.

16. In a clutch of the character described, the combination of a sleeve adapted to be mounted on a shaft and provided with a plurality of wedge surfaces, a series of segmental plates formed with a plurality of wedge shape surfaces which coöperate with the wedge surfaces on the sleeve, and means automatically operated when a roll supported by the clutch becomes loose to create rela-

tive movement between the sleeve and the segmental plates to cause the coöperating wedge surfaces to force the plates outwardly and frictionally engage the roll and take up the looseness.

17. In a clutch of the class described, the combination of a longitudinally movable sleeve formed with a plurality of peripherical wedge surfaces, a series of segmental plates mounted on the sleeve, each plate having a plurality of wedge surfaces which engage with and coöperate with the wedge surfaces on the sleeve, and means automatically operated when a roll supported by the clutch becomes loose to longitudinally move the sleeve to cause the coöperating wedge surfaces to force the segmental plates outwardly to frictionally engage the roll and take up the looseness.

18. In a clutch of the class described, the combination of a sleeve formed with a plurality of steep short inclined surfaces, a plurality of segmental plates mounted on the sleeve, each of said plates having a plurality of steep short inclined surfaces corresponding to and coöperating with the inclined surfaces on the sleeve, said plates being freely rotatable on the sleeve and each being independent and free of the other, and means operable by a roll supported on the clutch for causing rotation of the plates and creating relative longitudinal movement between the sleeve and plates to frictionally bind them and a roll supported by the clutch.

19. In a clutch of the class described, the combination of a sleeve formed with a plurality of steep short inclined surfaces, a plurality of segmental plates freely rotatable on the sleeve, each plate having a plurality of steep short inclined surfaces corresponding to and coöperating with the inclined surfaces on the sleeve, and means operating on the sleeve to create relative movement between the sleeve and segmental sections to cause the short steep inclined surfaces to ride one on the other and frictionally bind the plates and sleeve and a roll supported on the clutch, the segmental plates rotating independently of the sleeve during the time of the relative movement.

WILLIAM SHEAHAN.
